UNITED STATES PATENT OFFICE.

JAMES WILEY PHELPS, OF DETROIT, MICHIGAN.

PLUG-SOCKET.

1,028,957.

Specification of Letters Patent. Patented June 11, 1912.

Application filed April 9, 1909. Serial No. 488,999.

To all whom it may concern:

Be it known that I, JAMES WILEY PHELPS, a citizen of the United States of America, residing at Detroit, in the county of Wayne and State of Michigan, have invented certain new and useful Improvements in Plug-Sockets, of which the following is a specification, reference being had therein to the accompanying drawings.

10 The invention relates to a combined socket and tap for electric lamps, hereinafter referred to for convenience as a plug socket, and consists in an appliance of this character having a concealed controlling switch 15 for the lamp circuit provided with external actuating means, preferably in the form of a depending cord or string, the appliance being insertible within the usual permanent lamp socket and intended for use as an attachment in connection with lamps located out of the convenient reach of the user.

The invention further consists in the peculiar arrangement and combination of the parts comprising the plug socket, and in 25 certain details of construction as will be hereinafter set forth.

In the drawings,—Figure 1 is a vertical central section through my improved attachment; Fig. 2 is a cross section taken on line 30 $x-x$ of Fig. 1; and Fig. 3 is a similar section taken on line $y-y$ of the same figure.

In construction, the plug socket is formed of a tubular body A of insulating material, preferably though not necessarily porcelain, 35 divided into two oppositely-disposed socket sections B and C by an insulator head D preferably formed integral with the body. Within the socket portion B is located the usual threaded shell contact E having a 40 transverse flange portion F that seats upon the head and is secured thereto by a screw G. H is the usual center contact for the lamp-receiving socket B, secured to the head by a screw I which extends entirely through 45 the head as indicated.

J represents the plug contact of the attachment of the ordinary externally threaded shell construction, fitted at one end within the socket C and provided at its outer end 50 with the usual insulated center contact K.

L represents the controlling switch for the lamp circuit, which I have shown arranged within the socket C of the attachment. It is pivoted at one end to the head by the 55 screw I and is adapted to be brought into

and out of engagement with a contact M upon the head which is connected by a suitable conductor O to the center contact K.

The operating means for the switch is preferably a cord, as P, the switch being 60 of the type usually designated as a "pull-string" switch, the cord or string extending through a pair of apertured ears b upon the switch proper, knotted intermediate the ears to form an operative engagement, and the 65 ends extending the required distance below the attachment in a position conveniently accessible to the user.

As thus constructed, it will be seen that the center contacts H and K are electrically 70 connected through the switch, the switch pivot, contact, and usual conductor O, and the shell portions within the body sockets are connected through the securing screw G and a conductor Q extending from the 75 lower end of the securing screw to the shell a.

A novel and simple means of attachment is employed for uniting the shell of the plug contact J to the insulator body, and also for 80 forming electrical contact between the conductor Q and the plug shell. Within the wall of the socket C is formed a transverse opening or aperture c, which leads through the wall to the plug shell, as shown in Fig. 1. 85 Prior to the positioning of the plug within the insulator body, the end of the conductor Q is drawn through the aperture c and the shell of the plug subsequently inserted, making contact with the conductor as indicated. 90 A drop of solder is then inserted within the transverse opening c, the shell opposite the opening being first preferably tinned, which forms the desired electrical connection between the conductor and the shell, and at 95 the same time unites the shell to the insulator body, the solder forming a retaining stud upon the exterior of the shell which engages the aperture and holds the shell in its proper position. Preferably, three of these openings are formed in the shell at equidistant points, each filled or partially filled with 100 solder, for the purpose set forth.

In cases where an electric lamp is located in a position not easily accessible to the user, 105 the attachment may be employed, the lamp being removed from the terminal socket, the plug portion of the attachment inserted therein, and the lamp arranged within the attachment socket. The switch of the ter- 110

inal socket is then closed, and the operation of the lamp controlled solely through the operating switch within the attachment.

What I claim as my invention is,—

5 1. In a plug socket, the combination with a tubular insulator body, of an insulator head arranged transversely therein intermediate the body ends, a switch member pivoted upon one side of the head and a contact 10 therefor, and a center contact upon the opposite side of said head and secured to the latter by the switch pivot.

2. The combination of an insulator body having a recess or socket formed therein 15 of a size to receive the shell of a plug contact, and a lateral opening extending through the socket wall, a plug contact positioned within the recess, and a retainer for uniting the parts fixed upon the exterior of the plug 20 shell and engaging the opening in the wall of the recess.

3. The combination of an insulator body having a recess or socket formed therein, and an opening leading through the recess 25 wall, of a shell contact located within the recess, and a solder member upon the shell engaging the opening.

4. The combination of an insulator body having a recess or socket formed therein, 30 and an opening leading through the recess wall, of a shell contact located within the recess, a retainer for the shell engaging the opening, and a conductor within the body socket extending in operative relation to 35 the opening and embedded within the retainer.

5. The combination of an insulator body having a socket formed therein, and a transverse opening leading through the socket 40 wall, of a shell contact located within the socket, a conductor located within said socket extending within the opening, and material within said opening forming a connection between the body and shell and uniting 45 the latter with the conductor.

6. In a plug socket, the combination with a tubular insulator body, of an insulator head arranged transversely therein intermediate the body ends, a switch member 50 pivoted to said head, a contact for said switch member, and a center contact secured to the head by the pivot of the switch member.

7. The combination with a tubular insulator body, of an insulator head therein 55 dividing the interior of the body into complementary socket sections adapted to receive a lamp and a plug contact, a lamp switch having its movable member pivoted to said head, a contact member for said 60 switch also carried by the head, and a second contact member secured to the head by the pivot of the movable switch member.

8. The combination with an insulator body having a recess or socket formed therein, an 65 opening leading through the recessed wall, a shell contact located within the recess, and a retainer upon the shell for engaging said opening.

9. The combination of an insulator body 70 having an insulator head dividing the interior of the body into complementary socket sections, a shell contact positioned within one of the socket sections, a switch arranged within the other socket section having its 75 movable member pivoted to said insulator head, and a plug contact having a portion arranged within the last mentioned socket.

10. The combination of an insulator body having an insulator head dividing the interior of the body into complementary socket sections, a shell contact positioned in one of said socket sections, a plug contact having a portion thereof arranged within the other socket section, and a switch including a comparatively flat movable member arranged 80 within one of said sections and pivotally mounted upon the head.

11. The combination of an insulator body having an insulator head dividing the interior of the body into complementary socket sections, a shell contact positioned in one of said socket sections, a plug contact having a portion thereof arranged within the other socket section, a switch including a comparatively flat movable member arranged 85 within one of said sections and pivotally mounted upon the head, and a pull string for actuating said switch member having a portion thereof extending without the body. 90

In testimony whereof I affix my signature in presence of two witnesses.

JAMES WILEY PHELPS.
